UNITED STATES PATENT OFFICE.

SHERMAN M. FAIRCHILD, OF ONEONTA, NEW YORK.

PLATE PACK.

Application filed September 23, 1918. Serial No. 255,334.

To all whom it may concern:

Be it known that I, SHERMAN M. FAIRCHILD, a citizen of the United States, residing at Oneonta, in the county of Otsego and State of New York, have invented new and useful Improvements in Plate Packs, of which the following is a specification.

This invention relates to photographic plate packs, which essentially combine the usual commercial packages in which the plates are arranged for sale, and the adapter through which the plates are exposed in the camera.

The improvement contemplates the employment of a box in which the plates are sold comprising telescopic sections so constructed that the sensitized plates contained therein may be loaded in the adapter, exposed, changed and removed from the adapter in full daylight without detriment thereto.

The improved plate pack is constructed to simulate the usual commercial plate package in size and appearance, and in detail involves but a slight expense in manufacture over such commercial package. However, such detail permits the use of the plate pack in an adapter for the successive exposure of the plates in the camera, so that the usual commercial package will serve to retain the plates until they are desired for development.

Structurally, the improved pack combines a box-like member made up of telescopic sections, of the material of the usual commercial packages, or other material, as desired. One of the sections will receive the plates, while the other, which serves as a cover, is arranged so that a simple complete telescopic opening and closing thereof, removes the forward or exposed plate to a position in rear of but as a member of the plate pile. Therefore, the plate pack will enable the user to expose the plates successively in the camera, without possibility of light admission to the fresh plates, and simultaneously arrange the exposed plates in the original package form.

The invention will be described in the following specification, reference being had to the accompanying drawings, in which—

Figure 1 is a front elevation partly broken out of the improved plate pack, the outer

box section being shown at the limit of the outward movement.

Figure 2 is a vertical section of the same cut just inside of the inner box section.

Figure 3 is a transverse section through the inner box section, on line 3—3 of Fig. 2, the plates being shown in position therein.

Fig. 3^a is a detail section of a plate.

Figure 4 is a vertical section of the improved plate pack with a slightly modified plate operating means.

Figure 5 is a front elevation partly broken out.

The improved plate pack, in both the preferred and modified forms, is here shown as comprising a box-like member, including an inner section 1 and an outer section 2. The box-like member is preferably constructed of cardboard, as is the usual plate package of commerce and closely resembles such package in size and shape. The inner section is of a width, length and thickness to receive and house the desired number of plates, and in specific formation has the usual back 3, side walls 4, and bottom edge wall 5, the latter being, however, of somewhat greater thickness than the usual box end.

The front of the section 1 has a rectangular shaped opening 6 cut out of dimensions slightly smaller than the plates used to keep the latter from falling out. As aforesaid, the upper end of the section 1 is open except for the guide ledge 7, Fig. 1, or 7^a, Fig. 4. This ledge is formed to guide the plates from the exposing position to a position in rear of the plate piles, as will later appear. The guide ledge is secured to the side walls of the section, and is of a generally right-angled triangular shape in cross section, with the upper side straight as in Fig. 4 or slightly rounded as in Fig. 2. The forward wall of the ledge is spaced from the top of the front wall 8 of the section to permit a plate to pass therebetween, while the rear edge of the ledge is similarly spaced from the back of the section. The upper surface of the ledge is inclined toward the back or rear of the section to direct the lower edge of the plate being shifted.

The outer section of the pack 2 is fitted to telescopically embrace the inner section 1 and is therefore open at its lower end wall

to receive such inner section. The front wall 9 of the outer section has a rectangular shaped opening 2^a cut out of the same dimensions as the opening in section 1 and so placed that it will exactly coincide with the latter opening when the two sections are in closed relation.

The inner surface of the upper end wall 2^c of the section 2, is provided with a guide strip 10, having a downwardly and rearwardly inclined surface 11, beyond which is a square or flat surface 12. The surface 11 tends to guide the plates downwardly toward the rear, thus cooperating with the inclined surface of the legs 7, while the surface 12 acts to force the plates into such position that they will slip under the guide ledge 7 when pushed forward by spring 13.

The spring strips 13 are arranged on the inner surface of the back of the inner section 1, which strips are secured to the back at their upper ends and free at their lower ends. These strips serve to hold the plates pressed forwardly, or toward the front of the section, so that the front plate is always in the same plane. These springs also allow for any inequalities in the thickness of the plates. The springs will yield to permit the introduction of the exposed plate, as in the operation of the plate shifting.

The plates P used in this improved plate pack differ from the ordinary photographic plate in that they are provided with an opaque paper backing 22. This backing extends across the back and around the longer edges of the plate. It is fastened by some soluble adhesive along a narrow strip 9', on the emulsion side of the plate. As the paper backing is fastened only along this strip 9', the backing 22 may be readily torn off to permit examination of the image in developing. The pieces of paper still adhering along the strips 9 will soak off during development, thus leaving the developed plate in no way differing from those commonly used. Along the strips 9', the paper backing might preferably be doubled under as is shown in Figure 3^a, thus forming ledges 50 two layers thick along the longer sides of the plate. These ledges serve to keep the plates from rubbing on each other. They are of such width that the open space between them is equal to the width of the opening in sections 1 and 2. Being of this dimension, none of the picture area of the plate is sacrificed. This paper backing thus serves four purposes. First, it prevents the light striking the plate being exposed from penetrating through and fogging the plates 60 behind it. Second, it forms a ledge 9' on the emulsion side of the plate, which ledge prevents any possibility of scratching or rubbing the emulsion in the packing or shifting operations. Third, these ledges 65 serve as guides upon which the shift-

ing springs 17 can slide without injuring the sensitive emulsion. Fourth, the backing does away with any tendency toward chipping of the edges of the plate common to some of the existing plate magazines.

The plate shifting mechanism comprises two spring members 17 bowed toward the back or rear of the section, which are secured at their upper ends to the upper end wall of the outer section and formed at 75 their lower ends with rearwardly extending hooks or plate-engaging projections 15. These members 17 slide between the ledges 9' of the foremost plate and the front wall of the inner section 1, so that as the outer section is moved inwardly or in closing relation to the inner section, the projections 15 ride over the surface of the foremost plate, near the edges thereof and preferably on the ledges 9' formed of the paper backing with 85 which the plates are ordinarily provided. The inward limit of the outer section positions the projections 15 below the lower edge of such foremost plate, so that as the outer section is moved outwardly said foremost plate is withdrawn, moving up with the outer section. In closing movement the members 17 move in and are compressed against the ledges 9', and are so held by the edge of the plate being 95 withdrawn, during the inward and a part of the outward movement of the outer section. The bowed portion of the strips 17 are, it will be noted, on the forward surface of the plate being withdrawn, so that as the outer 100 section is withdrawn to a position in which the spring members 17 are free to act, such strips will move the withdrawn plate toward the back of the section. This positions the upper edge of such plate, following the 105 guiding surface 11 of the guide strip 10, beneath the pushing surface 12 of such strip. The lower edge of such plate is on the inclined surface of the ledge 7. As the outer section is moved inwardly to engage another 110 plate, the plate so withdrawn is forced down in rear of the plate pile, the springs 13 yielding to permit such placement.

The improved pack described is designed for use with an adapter, which forms the subject matter of a copending application for patent, Serial No. 258,305, filed October 15, 1918, and when so used, the outer section will be formed at the upper ends of the side walls with outstanding portions 18 forming shoulders 19 to engage parts of the adapter, while the inner section will have corresponding adapter engaging means 20 at the lower end edge.

The modified form shown in Figures 4 and 5, utilizes the members 14 which are provided with positioning spring strips 16 bowed rearwardly from the free end of the members 14 and functioning in the same manner as the members 17 shown in Figures 120 125 130

1 and 2. The upper end wall of section 1 extends at 18° beyond the side walls to form shoulders 19, and members 5 of section 2 are provided with pin holes 23 for engagement with an adapter.

Of course, before loading the plate pack in the adapter, the plates must be protected against light entrance through the two co-extensive openings in the front walls of sections 1 and 2. For this purpose a piece P' of cardboard or other light proof material the length and width of the plate is arranged in front of the first plate and covering the openings. This cardboard acts as a dummy plate for the first outward movement of the outer section, leaving the first sensitive plate in position to be exposed. Exposure in the camera will be had with the sections in closed relation, or 20 in open relation, as desired, as in either position the foremost plate is exposed to the light through the lens.

The meeting edges and portions of the sections 1 and 2 are, of course, to be formed 25 to avoid light entrance, the detail being here shown right angled as interfitting of the parts.

Having thus described the invention, what is claimed as new, is:—

30 1. A plate pack in which the plates are initially assembled for sale as a complete commercial package, said pack comprising telescopically related open faced sections, and means arranged in said plate pack to 35 shift first the free end and then the other end of the plates in the pack from one position to another in the telescopic movement of the sections.

2. A plate pack comprising telescopic sections both open throughout the sensitized area of the contained plates, and a dummy plate initially rendering the interior of the pack light proof against such openings, and plate shifting means operated in the movement of the sections to move rearwardly first the free end and then the other end of said plates.

3. A plate pack comprising an open faced plate-receiving section, an open faced operating section having telescopic relation to the receiving section, and means carried by the operating section to engage and move rearwardly first the free end and then the other end of the foremost plate in the receiving section from such position.

4. A plate pack comprising an open faced plate-receiving section, an open faced operating section having telescopic relation to the receiving section, and means carried by the operating section to engage and move rearwardly first the free end and then the other end of the foremost plate in the receiving section from such position to a position in rear of and as a member of the plate pile.

5. A plate pack comprising two relatively

movable open faced sections, one section adapted to receive a number of plates, and springs formed with hooks carried by the other section to engage and lift the foremost plate in the movement of the sections 70 and move first the free end and then the other end of said moving plate rearwardly.

6. A plate pack comprising two relatively movable open faced sections, one section adapted to receive a number of plates, and 75 springs formed with hooks carried by the other section to engage and lift the foremost plate in the movement of the sections, said springs being formed to move first the free end and then the other end of the shifting plates during the relative movement of the sections rearwardly.

7. A plate pack comprising two relatively movable open faced sections, one section adapted to receive a number of plates, and 80 springs formed with hooks carried by the other section to engage and lift the foremost plate in the movement of the sections, said springs being formed to move first the free end and then the other end of the shifting 85 plates during the relative movement of the sections rearwardly, and guiding means on both sections to direct such moving plate to a position in rear of the plate pile.

8. A plate pack comprising two relatively movable open faced sections, one section adapted to receive a number of plates, and 90 springs formed with hooks carried by the other section to engage and lift the foremost plate in the movement of the sections, said springs having means to move first the free end and then the other end of the shifting 95 plate rearwardly during the relative movement of the sections, and guiding means on both sections to direct such moving plate to a 100 position in rear of the plate pile, and means on the one section to force the moved plate to a position in rear of and as a member of the plate pile in relative movement of the sections in one direction.

9. A plate pack comprising two relatively movable open faced sections, one section adapted to receive a number of plates, and 110 springs formed with hooks carried by the other section to engage and lift the foremost plate in the movement of the sections, said springs having means to move first one end and then the other end of the shifting plate backward, and guiding members, one on each section, cooperating to direct such moving 115 plate to a position in rear of the plate pile, one of said guides having an inclined surface terminating in a flat butt end engaging with the end of the shifting plate when the movable sections are being closed.

10. A plate pack comprising two relatively movable sections, one section adapted to receive a number of plates, and springs 120 formed with hooks carried by the other section to engage and lift the foremost plate 125

in the movement of the sections, said springs having means to move first one end and then the other end of the shifting plate backward, and guiding members, one on each section, cooperating to direct such moving plate to a position in rear of the plate pile, each guide member having an inclined surface,

one of said surfaces terminating in a butt end and serving to force the moved plate to a position in the rear of the plate pack in relative movement of the sections in one direction.

In testimony whereof I affix my signature.

SHERMAN M. FAIRCHILD.
